UNITED STATES PATENT OFFICE.

SUSANNA COCROFT, OF NEW YORK, N. Y.

FACE LIFTER.

Application filed March 6, 1925. Serial No. 13,566,

This invention relates to a lifting device for the facial and neck muscles, and has for its object to provide, in a manner as herein-after set forth, a device of the class referred to, with means capable of being detachably secured to the sides of the face to elevate the facial and neck muscles for the purpose of removing wrinkles, thereby restoring the skin of the face and neck to its natural condition, that is smoothed out and free from wrinkles, so that the face takes on a brighter and more youthful expression.

It is well known that the sagging of the muscles of the face will cause wrinkles to form from nose to mouth, in the cheeks and in the neck, and further that when the face begins to sag, due to the sagging of the facial muscles, there is a dragging about the eyes causing the face to have a tired look, but by lifting and holding the facial muscles for suitable periods, which is provided for by employing the removable muscle lifting and holding device, in accordance with this invention, this dragging sensation is relieved, the eyes are wondrously rested, the expression of the face is changed, and one will look substantially the same as before the facial muscles began to lose their tone, as the application of the device will cause the lines of the neck and about the mouth and eyes to smooth out due to the lifting of the muscles referred to.

Further objects of the invention are to provide a removable facial and neck muscles lifting and holding device for the purpose referred to, in a manner as hereinafter set forth, which is simple in its construction and arrangement, strong, durable, compact, thoroughly efficient and convenient in its use, and inexpensive to manufacture.

With the foregoing and other objects in view, the invention consists of the novel construction, combination and arrangement of parts, as hereinafter more specifically described and illustrated in the accompanying drawings wherein is shown an embodiment of the invention, but it is to be understood that changes, variations and modifications can be resorted to which fall within the scope of the claim hereunto appended.

In the drawings wherein like reference characters denote corresponding parts throughout the several views:

Figure 1 is a side view of a head showing the adaptation therewith of a muscle lifting

and holding device in accordance with this invention.

Figure 2 is a plan view illustrating a pair of face muscle lifters, in accordance with this invention, detachably secured to a boudoir cap.

Figure 3 is an elevation, partly broken away, of a facial muscle lifter, in accordance with this invention.

Figure 4 is a section on line 4—4, Figure 3.

Figure 5 is an enlarged sectional view on line 5—5, Figure 3.

Figure 6 is an elevation of a modified form.

Referring to Figure 1 of the drawings, a facial muscle lifter, in accordance with this invention, is generally referred to by the reference character 1, and it is illustrated in the position with respect to the head 2 of a person. The lifter 1 is concealed by the hair.

Referring to Figure 2 of the drawings, 3 indicates a boudoir cap and to which is detachably connected, by any suitable means, as indicated at 4, a pair of facial muscle lifters 1, in accordance with this invention. The lifters 1 are arranged in spaced relation. The lifters 1 are adjustably connected, as indicated at 5 in Figure 1.

Referring to Figures 3, 4 and 5, a facial muscle lifter, in accordance with this invention, comprises a flexible stay member 6 enclosed in a fabric casing 7, which is extended from one edge of the member 6, as at 8. The casing 7 is enclosed by a folded strip of fabric 9. The folds of said strip are indicated at 10 and 11 and which project beyond the extended portion 8 of the casing 7, as at 12, 13 respectively.

Extending through the portion 8 of the casing 7, as well as the folds 10 and 11, is a series of spaced clamping members 14 for detachably connecting a face adhering member 15 to the body portion, and said member is formed of an adhesive fabric, or a strip of silk or other suitable material can have an adhesive substance applied thereto for the purpose of connecting the member to the face. The clamping members are arranged against the outer faces of the projecting portions 12, 13 of the folds 10, 11 respectively, and further project beyond the lengthwise edges of the folds. The member 15 is of a width as to extend a substantial distance

from the clamping members 14, and the member 15 is arranged between the extended portions 12, 13 of the folds 10, 11 respectively.

5 Arranged against the outer face of the body portion of the lifter and of a width to conceal the clamping members 14, is a tape 16, which is secured in proximity to its rear edge, by a row of stitching 17 to the strip 10 at the outer side of the bend thereof.

10 The tape 16 not only conceals the clamping members 14, but also conceals the ends of a pair of equalizing members, and the said ends of said members are secured to 15 the body portion and to the tape 16 by the row of stitching 17.

One of the equalizing members is referred to generally by the reference character 18 and the other generally by the reference 20 character 19. The member 18 is bent upon itself to provide an outer and an inner portion 20, 21 respectively, and the member 19 is bent upon itself to form an outer and an inner portion 22, 23 respectively. The portion 25 20 of the member 18 is secured to one end of the body portion of the lifter, and the portion 22 of the member 19 is secured to the opposite end of the body portion of the lifter. The portion 21 of the member 18 is 30 secured to the body portion of the lifter at a point between its transverse center and one end of said body portion, and the portion 23 of the member 19 is secured to the body portion of the lifter at a point between its 35 transverse center and its other end. The portion 21 of the member 18 is arranged in proximity to the portion 22 of the member 19, and the portion 23 of the member 19 is arranged in proximity to the portion 20 of the 40 member 18.

The portions 20, 21, 22 and 23 are disposed at an inclination, and the inclination of the portions 20, 23 is opposite with respect to the inclination of the portions 21, 22. The portion 45 20 of the member 18 extends at a greater inclination than the portion 23 of the member 19, and the portion 22 of the member 19 extends at a greater inclination with respect to the inclination of the portion 21 of the member 18.

The equalizing members 18 and 19 are 50 slidably coupled together by means of an oval-shaped disk 24 formed with a pair of lengthwise extending spaced slots 25, 26. The member 18 extends through the slots 25 and 26, and the member 19 extends through the slot 26.

Attached to the disk 24 is an elastic connecting member 27 of any suitable length. 55 The connecting member 27 of one lifter is provided with any suitable means for adjustably securing it to the connecting member 27 of the other lifter, as indicated at 5 in Figure 1. In Figures 1 to 5, both inclusive, the 60 face adhering member 15 is rectangular in

contour and of a length substantially equal to the length of the body portion of the lifter. The width of the member 15 can be as desired.

In the modified form shown in Figure 6, 70 the body portion of the lifter is constructed in the same manner as the body portion disclosed in Figure 3, the difference between the form shown in Figure 6 and that shown in Figure 3 is that the body portion thereof 75 is of less length than the body portion disclosed in Figure 3, and but one equalizing member is employed in the modified form and such equalizing member is indicated at 28. The face adhering member is indicated 80 at 29 and is angle-shaped in contour so that it can be applied to the forehead of the user.

The member 28 has slidably mounted thereon a disk 30 of the same construction as the disk 24, and to the disk 30 is secured 85 a connecting member 31 of the same construction as the connecting member 27. Preferably in the form shown in Figure 6, the face adhering member 29 projects from each end of the body portion of the lifter. 90 Otherwise than that as stated, the construction shown in Figure 6 is the same as that shown in Figure 3.

The face adhering member is provided 95 with any suitable adhesive so that it will adhere to the face when the lifter is employed.

The manner of applying a muscle lifting and holding device, in accordance with this invention is as follows:

With the fingers on the hair just above 100 the ear, run them back to the crown of the head, bringing the upper hair forward and fastening it on the top of the head with a hair pin. See that the face is clean. If it is oily, the face adhering member will not 105 adhere as strongly. Then apply to the adhesive on said member just enough water or saliva to moisten the same. Do not make it too wet. Or the fabric forming the face adhering member can have an adhesive substance applied thereto. Then place the lower end of the face adhering member on the face just opposite the point of projection of the ear. Hold this on and extend the member upwardly to the temples just in front of 110 the hair line, as shown in Figure 1. See that the face adhering member is smooth on the face and hold it a few moments until it is dry. When the face adhering members are 115 firmly secured to the face in the position as stated, the elastic connecting members are secured together at the top of the head by the securing means therefor. The pull on the body portion of the lifters is equalized 120 by the equalizing members. The equalizing members and connecting members, when the device is used, are concealed by the hair. See Figure 1. When the pull is had on the body portion of the lifters, the muscles are 125 lifted to the desired extent, and after which 130

the connecting members are secured together in adjusted position. The device is worn any desirable period, preferably during the day, but can be worn at night and is further concealed if the lifters are detachably connected to a boudoir cap.

It is thought that the many advantages of a facial muscle lifting and holding device, for the purpose referred to and in accordance with this invention, can be readily understood, and although the preferred embodiment of the invention is as illustrated and described, yet it is to be understood that changes in the details of construction can be had which will fall within the scope of the invention as claimed.

What I claim is:—

A facial muscle lifting device for detachable connection to one side of the face comprising a flexible body portion of rectangu-

lar contour having projecting forwardly therefrom a face adhering member, a pair of non-elastic equalizing straps, each of said straps having one end positioned at one end of said body portion and its other end positioned adjacent the opposite end of said body portion, means for connecting the ends of said straps in spaced relation to the rear of the body portion, a slide provided with a pair of slots, one of said straps extending through one of said slots and the other of said straps extending through the other of said slots, and an elastic connecting member having an end thereof attached to one of the slots in said slide, said slide shiftably mounted on said pair of straps.

In testimony whereof, I affix my signature hereto.

SUSANNA COCROFT.
